UNITED STATES PATENT OFFICE

99,840

DESIGN FOR A WASH MIT

Anna Abraham, Detroit, Mich.

Application August 7, 1935, Serial No. 57,987

Term of patent 3½ years

To all whom it may concern:

Be it known that I, Anna Abraham, a citizen of the United States, residing at Detroit, in the county of Wayne and State of Michigan, have invented a new, original, and ornamental Design for a Wash Mit, of which the following is a specification, reference being had to the accompanying drawing, forming part thereof.

Fig. 1 is a front view of a wash mit embodying my invention.

Fig. 2 is a side view thereof.

Fig. 3 is a view taken from the bottom of the wash mit.

I claim:

The ornamental design for a wash mit, as shown.

ANNA ABRAHAM.
